(57) **CLAIM**

The ornamental design for an artificial boar eye, as shown and described.

DESCRIPTION

FIG. 1 is a top plan view of an artificial boar eye of this invention;

FIG. 2 is a bottom plan view of the artificial boar eye of FIG. 1 showing the notch therein;

FIG. 3 is a front elevation view of the present invention;

FIG. 4 is a rear elevational view thereof; and,

FIG. 5 is a side elevational view of the artificial boar eye, the opposite side being a mirror image thereof.

The stippling depicted in the accompanying drawings depicts surface contour only and does not depict any texture, color, shading or other characteristic.
